CLAIM

The ornamental design for a stand for photographic or cinematographic camera, as shown and described.

DESCRIPTION

FIG. 1 is a front, left, and top perspective view of a stand for photographic or cinematographic camera showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear, right, and bottom perspective view thereof;

FIG. 9 is an enlarged view of the portion of the stand for photographic or cinematographic camera shown in the area designated as 9 in FIG. 4;

FIG. 10 is an enlarged view of the portion of the stand for photographic or cinematographic camera shown in the area designated as 10 in FIG. 5; and,

FIG. 11 is an enlarged view of the portion of the stand for photographic or cinematographic camera shown in the area designated as 11 in FIG. 5.

The broken lines in the drawings are for the purpose of illustrating portions of the stand for photographic or cinematographic camera that form no part of the claimed design.
